ABSTRACT

A counter-top microwave oven comprises an upstanding box-like metal wall structure defining a heating cavity, a microwave generator, transmission means including a probe antenna for radiating the microwaves into the heating cavity from the top thereof, and tuning means disposed in the heating cavity adjacent to the top thereof, the cavity being so dimensioned and the antenna and tuning means being so positioned as to excite in the cavity a predetermined low impedance transverse magnetic field mode and a predetermined high impedance transverse electric field mode having a low impedance region in the portion of the heating cavity in which food is normally placed. Two alternative positions of the tuning means for establishing the preferred field patterns are disclosed.

FIG.1

FIG. 2

FIG. 3

MICROWAVE OVEN HAVING TM AND TE MODES

BACKGROUND OF THE INVENTION

The present invention relates to electronic heating apparatus of the type commonly referred to as a microwave oven, and specifically to a microwave oven of the countertop variety which has a heating cavity with dimensions generally comparable to a wavelength of the microwave energy used. More particularly, the present invention is an improvement of the invention disclosed in our copending U.S. application Ser. No. 430,730, filed Jan. 4, 1974, entitled "MICROWAVE OVEN WITH PREFERRED MODES," and assigned to the assignee of the present invention.

In that copending application, there were disclosed a number of different forms of a microwave oven heating enclosure, the dimensions and antenna location of which provided for the excitation in the heating cavity of two complementary transverse electric (TE) field modes, thereby resulting in a heating pattern which afforded fairly uniform heating of a wide variety of low impedance food loads.

As an alternative means for achieving composite field patterns having improved heating characteristics in microwave ovens, attempts have been made to utilize a low impedance transverse magnetic (TM) wave to improve the microwave heating of low impedance food by reducing the voltage standing wave ratio in the heating cavity. Results of these attempts have not been entirely satisfactory because a region in the center of the heating cavity did not afford adequate heating. One solution to this problem which has given good results is the use of a near field device disposed beneath the food load to heat food in the central region of the heating cavity. However, this near field device requires the use of a dielectric shelf for supporting the food load.

SUMMARY OF THE INVENTION

It is a general object of the present invention to provide an electronic heating apparatus characterized by a heating cavity having excited therein a predetermined transverse magnetic field mode and a predetermined transverse electric field mode, resulting in a composite field pattern which provides uniform heating of low impedance foods throughout the heating cavity.

Another object of this invention is to provide an electronic heating apparatus of the character described, which includes coupling means whereby the TM and TE modes may both be excited from the same antenna.

An important object of the present invention is to provide an electronic heating apparatus for heating a low impedance body, the apparatus comprising a metal enclosure in the form of a rectangular parallelepiped including a top wall, a bottom wall, a front wall, a rear wall and two opposed side walls defining a heating cavity for receiving therein a body to be heated, source means including a probe antenna electrically coupled to the heating cavity along the top wall for transmitting microwave energy of a predetermined wavelength λ into the heating cavity to excite therein two predetermined electromagnetic field modes, the heating cavity having an electrical width substantially equal to 1.2λ and an electrical height substantially equal to 0.633λ and an electrical depth substantially equal to 1.1λ , and tuning means disposed in the heating cavity adjacent to

the top thereof, one of the predetermined electromagnetic field modes being a relatively low impedance transverse magnetic field mode, the other of the predetermined electromagnetic field modes being a relatively high impedance transverse electric field mode having a relatively low impedance region generally centrally of the heating cavity, whereby there is established in the heating cavity an electromagnetic field pattern providing uniform heating of an associated low impedance body.

Further features of the invention pertain to the particular arrangement of the parts of the electronic heating apparatus whereby the above-outlined and additional operating features thereof are attained.

The invention, both as to its organization and method of operation, together with further objects and advantages thereof, will best be understood by reference to the following specification taken in connection with the accompanying drawings.

BRIEF DESCRIPTION OF THE DRAWINGS

FIG. 1 is a front perspective view of a microwave oven including a heating enclosure constructed in accordance with and embodying the features of the present invention;

FIG. 2 is a diagrammatic transparent perspective view of a first form of the heating cavity of the electronic heating apparatus of FIG. 1 for producing transverse magnetic and transverse electric field modes; and

FIG. 3 is a view similar to FIG. 2 showing a second form of the heating cavity of the electronic heating apparatus of FIG. 1.

DESCRIPTION OF THE PREFERRED EMBODIMENTS

Referring now in particular to FIGS. 1 and 2 of the drawings, there is illustrated a microwave oven, generally designated by the numeral 10, constructed in accordance with and embodying the features of the present invention. The microwave oven 10 is adapted for placement on top of a table or counter and is housed in a cabinet which includes an upstanding front panel 11, a rear wall 12, a top wall 13, a bottom wall 14 and a pair of opposed side walls 16 and 17. Mounted within the oven cabinet alongside the front panel 11 is a heating enclosure, generally designated by the numeral 20, including a top wall 21, a bottom wall 22, a rear wall 23 and a pair of opposed side walls 24 and 26, the front of the heating enclosure 20 being closed by a door 15 which, in the closed position thereof, forms the front wall of the heating enclosure 20, which enclosure is generally in the form of a rectangular parallelepiped.

Thus, the heating enclosure 20 serves to separate the interior of the oven cabinet into a heating cavity defined within the heating enclosure 20 for receiving therein and heating a food load 18, and a machinery compartment 25 between the heating enclosure 20 and the oven cabinet walls 12, 13, 14 and 17. Mounted in the machinery compartment 25 is a magnetron 27, a power supply 28 and a coaxial microwave transmission line (not shown) which transmits microwave energy from the magnetron 27 to the interior of the heating enclosure 20.

The magnetron 27, power supply 28 and transmission line may be of any suitable type, but preferably they are substantially identical in construction and operation to

the magnetron, power supply and transmission line disclosed in the aforementioned copending U.S. application Ser. No. 430,730, whereby there is here described in detail only so much of the structure of the microwave oven 10 as is necessary to an understanding of the present invention.

The coaxial transmission line from the magnetron 27 has an outer conductor which is designated by the numeral 29 in FIG. 2, and terminates at the top wall 21 of the heating enclosure 20, the inner conductor of the transmission line terminating at a probe antenna 30, which projects vertically downwardly into the heating cavity through a complementary opening in the top wall 21 of the heating enclosure 20. It is an important feature of the present invention that the antenna 30 is so positioned and the heating enclosure 20 is so dimensioned that both a TM field mode and a TE field mode are excited in the heating cavity.

In the form of the heating enclosure illustrated in FIG. 2, the electrical dimensions of the heating cavity are in accordance with the relationships

$$\lambda = 2 / \sqrt{(1/x)^2 + (1/y)^2 + (1/z)^2}$$

and

$$\lambda = 2 / \sqrt{(1/x)^2 + (2/z)^2}$$

wherein x corresponds to the width of the heating cavity, y corresponds to the height of the heating cavity and z corresponds to the depth of the heating cavity. From these relationships it follows that

$$z = \sqrt{3}y$$

The impedance Z_0 of the TM mode is

$$Z_0 = 377 / \sqrt{1 - (\lambda/\lambda_0)^2}$$

and the impedance for the TE mode is

$$Z_0 = 377 / \sqrt{1 - (\lambda/\lambda_0)^2}$$

where λ_0 is the cutoff wavelength for the heating cavity. It has been found that in order to achieve a suitably low impedance, the dimension D of the heating cavity in the direction of power flow should be

$$D \geq 0.55 n \lambda$$

It has been found that when the heating enclosure 20 has dimensions according to these relationships, such that $x = 1.2 \lambda$, $y = 0.633 \lambda$ and $z = 1.1 \lambda$, and when the antenna 30 is positioned as illustrated in FIG. 2 substantially midway between the side walls 24 and 26 and approximately $z/4$ from the rear wall 23, there are produced in the heating cavity the $TM_{1,1,1u}$ and the $TE_{1,0,2z}$ electromagnetic field modes, wherein the numeral subscripts represent, respectively, the field variations in the x , y and z directions, and the letter subscript indicates the direction of power flow.

A conductive tuning rod or probe 35 is disposed substantially centrally of the top wall 21 of the heating enclosure 20 and extends vertically downwardly into the heating cavity, the tuning probe 35 serving to adjust the heating pattern to compensate for field distortions which are present with a TM and a TE mode. The $TM_{1,1,1u}$ mode is a low impedance mode, while the $TE_{1,0,2z}$ mode is a high impedance mode which, however, has a low impedance region generally centrally of the heating cavity in the position where food is normally placed. Thus the $TM_{1,1,1u}$ and $TE_{1,0,2z}$ modes cooperate to provide a uniform heating of a wide variety

of low impedance food loads in various positions in the heating cavity. Preferably, the probe antenna 30 and the tuning probe 35 are so dimensioned as to provide equal heating to a food load placed either in the back or the front of the heating cavity.

Referring now to FIG. 3 of the drawings, there is illustrated an alternative arrangement of the heating enclosure 20, which is substantially identical to the arrangement illustrated in FIG. 2, except that there is provided a tuning probe 45 extending vertically downwardly into the heating cavity from the top wall 21 at a location thereon substantially midway between the side walls 24 and 26 and spaced approximately $z/4$ from the front wall or oven door 15. The same electromagnetic field modes are excited in both the arrangements of FIGS. 2 and 3, the only difference being slight adjustments in the composite heating patterns.

From the foregoing, it can be seen that there has been provided an improved electronic oven which affords uniform heating of a wide variety of low impedance food loads by the use of TM and TE field modes in the heating cavity.

More particularly, there has been provided an electronic heating apparatus which includes a heating cavity so dimensioned and a probe antenna and tuning member so positioned adjacent to the top of the heating cavity that there is produced in the heating cavity a predetermined low impedance TM field mode and a predetermined high impedance TE field mode having a low impedance region in the position where food is normally placed in the heating cavity.

There has also been provided an electronic heating apparatus which utilizes both TM and TE field modes, without necessitating the use of a near field device to excite the TM field mode.

While there have been described what are at present considered to be the preferred embodiments of the invention, it will be understood that various modifications may be made therein, and it is intended to cover in the appended claims all such modifications as fall within the true spirit and scope of the invention.

What is claimed is:

1. Electronic heating apparatus for heating a low impedance body, said apparatus comprising a metal enclosure in the form of a rectangular parallelepiped including a top wall, a bottom wall, a front wall, a rear wall and two opposed side walls defining a heating cavity for receiving therein a body to be heated, source means including a probe antenna electrically coupled to said heating cavity along said top wall for transmitting microwave energy of a predetermined wavelength λ into said heating cavity to excite therein two predetermined electromagnetic field modes, said heating cavity having an electrical width substantially equal to 1.2λ and an electrical height substantially equal to 0.633λ and an electrical depth substantially equal to 1.1λ , and tuning means disposed in said heating cavity adjacent to the top thereof, one of said predetermined electromagnetic field modes being a relatively low impedance transverse magnetic field mode, the other of said predetermined electromagnetic field modes being a relatively high impedance transverse electric field mode having a relatively low impedance region generally centrally of said heating cavity, whereby there is established in said heating cavity an electromagnetic field pattern providing uniform heating of an associated low impedance body.

2. The electronic heating apparatus set forth in claim 1, wherein said antenna is disposed substantially midway between said side walls and is spaced from said rear wall an electrical distance one-fourth the depth of said heating cavity.

3. The electronic heating apparatus set forth in claim 1, wherein said antenna is disposed substantially midway between said side walls and is spaced from said rear wall an electrical distance one-fourth the depth of said heating cavity, said tuning means being disposed centrally of said top wall.

4. The electronic heating apparatus set forth in claim 1, wherein said antenna is disposed substantially midway between said side walls and is spaced from said rear wall an electrical distance one-fourth the depth of said heating cavity, said tuning means being disposed substantially midway between said side walls and being spaced from said front wall an electrical distance one-fourth of the depth of said heating cavity.

5. The electronic heating apparatus set forth in claim 1, wherein λ is approximately equal to 12.9 inches.
